Inventor
Charles H. Roehm

By Ramsey Hoguet.
Attorney

UNITED STATES PATENT OFFICE.

CHARLES H. ROEHM, OF WEST NEW YORK, NEW JERSEY.

SADIRON.

Application filed August 10, 1923. Serial No. 656,750.

To whom it may concern:

Be it known that I, CHARLES H. ROEHM, a citizen of the United States, and a resident of West New York, county of Hudson, 5 State of New Jersey, have invented an Improvement in Sadirons, of which the following is a specification.

This invention relates to handles for electrically heated sad irons and refers more 10 particularly to means for controlling the current to the heating element of the iron.

An object of this invention is to provide a means by which the electric current is automatically switched off whenever the iron 15 is not in use, thus eliminating danger of fire and the burning out of the heating element.

Another object of this invention is the provision of means whereby the heating circuit may be retained closed when it is desired to initially heat the iron.

Other objects and advantages of this invention will be apparent from the following description taken in conjunction with the accompanying drawings which illustrate 25 the preferred embodiment of the invention and in which similar characters of reference designate similar parts in the several views.

In the drawings

Figure 1 is a cross sectional view of the 30 handle, showing the switch in open position,

Fig. 2 is a cross sectional view showing the switch in closed position, and

Fig. 3 is a sectional view on the line 3-3, Fig. 2.

Referring now, more particularly to the drawings, the numerals 1 and 8 designate the usual handle standards which are secured at their lower ends to an iron body (not shown), and support therebetween at 40 their upper ends a handle, designated generally as H.

The handle H comprises a tubular body formed of suitable insulating material and closed at each end by a removable plug, as 45 shown at 3 and 4; standard 1 extending through the material of body and being secured to plug 3 by a screw 5 or the like. The plug 4 is provided with an aperture 6 extending therethrough, said plug being internally threaded to receive a bushing 7 of insulating material. The upper end of standard 2 extends through body of the handle H and is secured to the bushing 7. The usual conductors 8 and 9 are provided,

conductor 9 passing directly to the iron 55 body through a plug 10. Conductor 8 passes into the handle as will be hereinafter described.

The body of the handle H is provided with a slot or recess 11 which communicates 60 with the interior of the handle, and positioned within said slot and pivotally mounted therein is an operating lever L formed of sections 12 and 13. In practice I have found it highly desirable to so form the slot 11 that 65 the material cut therefrom shall form the portion of the lever designated as 12, this presenting a finished appearance and resulting in great economy of material. The section 13 is formed of insulating material 70 and is secured to the under face of section 12 by means of screws 14 or the like. One end of section 13 is formed into a cam 15, which cam, through pivot pin 16 mounts the entire operating lever within the slot 11 and 75 body of the handle C.

The cam 15 is provided with positioning faces 17 and 18 and a boss 19. As shown clearly in Figs. 1 and 2, the faces 17 and 18 are adapted to contact with the free end of 80 a flat spring 20 the other end of which is secured between a bearing plate 21 and plug 3 by means of a screw 22 or the like. The cam 15 is also provided with a contact face 18' arranged between the boss 19 and 85 positioning face 18.

Secured within the body of the handle H by means of screws 23 or the like is an insulating support 24 which supports thereupon by means of screws 25 or the like, a 90 conductive contact spring 26, the free end of which is substantially U-shaped forming a contact portion 27 having a contacting face 28 which is adapted to contact with the bent-over end 29 of a C-shaped spring 30. 95 The spring 30 is secured to the body of the handle H by means of the before mentioned supporting block 24, and is provided with a rearwardly extending end 31 to which is secured a conductor 32 which passes through 100 an insulator 33 extending through the bushing 7 and leads to the heating element of the iron.

The before mentioned conductor 8 also passes through the insulator 33 and terminates in a conductor 34 which is connected to the conductive contact spring 26 by one of the screws 25.

The C-shaped end 29 of the spring 30 is provided with a protrusion 35 which is adapted to contact with the boss 19 upon certain movement of the lever L.

- 5   In operation, as shown in Fig. 1 the circuit to the heating element is normally open and should it be desired to initially heat the iron associated with the handle, the lever L is swung to the position illustrated in dotted 10 lines in Fig. 2; the face 17 retaining the lever in the position shown by contacting with the spring 18. It will be apparent that the face 18' will engage the contact portion or protrusion 35 of the spring 30 and force 15 section 29 thereof in contact with the U-shaped end of spring 26 thus closing the circuit through 34, 26 and 27 to 29, 30, 31, and 20 32 to the heating element of the iron and out through lead 9.
- 20   The iron being initially heated, an operator thereof may then swing the lever L on its pivot to the position shown in full lines in Fig. 2, whereupon boss 19 contacts with portion 35 of spring 30, making contact with 25 spring 26 and closing the circuit as above described.

- It will be apparent that contact between 28 and 29 will be automatically broken as 30 soon as the operator's hand is withdrawn from the handle because of spring 20 which will immediately return the lever to the position illustrated in Fig. 1, for the reason that when the parts are in the position illustrated in full lines in Fig. 2 the spring 20 35 is under tension.

- From the above, it can also be seen that the cam is provided with faces which position the lever L and maintain the springs 26 and 30 either in contact or out of contact. 40 It is believed that the operation of the device will be fully understood by those skilled in the art, but I desire it understood that various changes in the form and proportions of the device may be made within 45 the scope of the appended claims without departing from the spirit of the invention.

What I claim as new and desire to secure by Letters Patent of the United States is:

1. A handle for an electrically heated sad iron or the like comprising a hollow body 50 having a slot communicating with the interior thereof, a lever pivoted in said slot, a cam secured to one end of said lever and provided with positioning faces and a boss, 55 spring means cooperating with said faces whereby said cam and lever are automatically returned to their normal positions or retained in a fixed position, and normally separated conductors adapted to cooperate with said cam whereby they are forced into 60 contact.

2. A handle for an electrically heated sad iron or the like comprising a hollow body having a slot communicating with the interior thereof, a lever, a cam within said body and mounting said lever, electrical conductors leading into said body and terminating in normally spaced contact springs, one of which is adapted to cooperate with said 65 cam, resilient means cooperating with said cam whereby said cam temporarily retains said contact springs in contact or said cam is maintained in a fixed position and said contact springs in contact.

3. A handle for an electrically heated sad iron or the like comprising a hollow tubular body, conductors leading into said body and terminating in spaced contact springs at one end thereof, a lever mounted in said body, a cam secured to said lever, means on 70 said cam adapted to cooperate with the contact springs whereby the latter are manually and temporarily retained in contact, means also on said cam for positively retaining the cam in a fixed position and said contact 75 springs in contact, and resilient means for normally positioning said cam.

In testimony whereof, I have signed my name to this specification this 4th day of August 1923.

CHARLES H. ROEHM.
